UNITED STATES PATENT OFFICE

WILLIAM E. BIHL AND AXEL RAMCLAW, OF CHICAGO, ILLINOIS, ASSIGNORS TO ZERO-ZONE, INCORPORATED, OF CHICAGO, ILLINOIS, A CORPORATION OF DELAWARE

EVAPORATOR

Application filed March 3, 1930. Serial No. 432,916.

This invention relates to refrigeration units, and more particularly to a refrigeration unit of the type now commonly known in the art as an evaporator.

5 In refrigerating systems of what is known as the flooded type used in dwellings, apartment houses, and similar establishments, an evaporator is mounted in a compartment of the refrigerator structure. This evaporator 10 comprises a barrel or container, sometimes referred to as a boiler, and a plurality of tubular members or pipes opening into the container and extending therefrom into the compartment of the refrigerator. A suitable refrigerant, sulphur dioxide is extensively used, 15 is supplied to this container in liquid form from a compressor.

This liquid refrigerant flows from the lower portion of the container to the tubular members or pipes and absorbs the heat in the compartment of the refrigerator thereby lowering the temperature thereof, the refrigerant being thereby vaporized. The vaporized refrigerant collects in the upper portion of 25 the container from which it is withdrawn and compressed and then returned to the container in liquid form. The operation of these units or evaporators is well understood in the art and need not be described in detail.

30 The evaporators or units above referred to necessitate a plurality of openings in the body of the container, in which openings the ends of the pipes are secured by soldering. This construction is highly objectionable in many respects. The numerous pipes have to be soldered in the container by hand, a tedious and costly job. There is always the possibility of a defective joint, with resulting leakage, since the human equation can not 35 be eliminated. Even though the joints be properly made at first, there is great danger of one or more of these joints becoming broken or opened in handling and shipping of the unit since the pipes extending therefrom are 40 of appreciable length and, when subjected to pressure, exert a great leverage effect at the joints. These evaporators or units are extensively used in apartment houses and are commonly installed in multiple sets of eight- 45 een or more units or evaporators.

This means that there is, in a system of this sort, one hundred pounds or more of refrigerant. If the slightest leak should occur in any of the evaporators or units included in the system, there is the possibility of discharging this 100 pounds of refrigerant, in the form of gas or vapor. When this occurs a very serious situation develops which might quite possibly result in the loss of life. This is, of course, the most serious objection 55 to the form of evaporator or unit now commonly used in the flooded system of refrigeration, referred to. From the standpoint of production, the necessity of hand soldering the pipes or tubes into the container is objectionable as greatly adding to the cost of the unit. A leak, in addition to endangering 60 life, is highly objectionable as creating an offensive odor, preventing efficient operation of the system, and for various other reasons 65 which need not be enumerated in detail.

We have found that it is possible to avoid the above noted objections to the present form of evaporator by providing means whereby the heat in the compartment containing the evaporator or unit can be readily conducted to the container and the liquid refrigerant therein without employing pipes or like elements through which the refrigerant circulates. This avoids all necessity for 75 providing a multiplicity of openings in the body of the container into which the ends of the pipes are soldered, avoiding the possibility of breaking of the joints and resulting leakage.

80 Our invention comprises, in its broader aspects, the provision of a container for a refrigerant, this container having associated therewith members of high heat conductivity 85 which are thermally connected to the container and extend into the compartment of the refrigerator structure, such members serving to conduct the heat to the container which, in turn, conducts the heat to the refrigerant therein which is thus vaporized, the vaporized refrigerant being drawn off or permitted to escape from the container. In this manner, the compartment of the refrigerator is effectively cooled and main- 90 95 100

tained at a temperature proper for efficiently conserving food stuffs.

It is one of the main objects of our invention to provide an evaporator or refrigerating unit in which the body of the container is continuous and unbroken and possibility of leakage therefrom due to defective joints is eliminated. A further object is to provide a unit of simple and inexpensive but rugged and highly efficient construction. Further objects and advantages will appear from the detailed description.

In the drawings:

Fig. 1 is a front view of a refrigerating unit constructed in accordance with our invention, as applied;

Fig. 2 is a section taken substantially on line 2—2 of Fig. 1;

Fig. 3 is a side view of the unit as applied;

Fig. 4 is a sectional view, on an enlarged scale, taken substantially on line 4—4 of Fig. 2;

Fig. 5 is a sectional view taken substantially on line 5—5 of Fig. 2;

Referring more particularly to Figs. 4 and 5, our unit includes a cylindrical container or barrel 1 closed at one end by an integral head 2. A flanged ring 3 is suitably secured in the other end of the barrel so as to have a fluid tight closure therewith. A head 4 is secured in a suitable manner, as by means of cap screws 5, to ring 3, a gasket 6 being interposed between the head and the ring so as to form a fluid-tight closure therebetween.

This head 4 is provided with an inlet opening 7 for admission of refrigerant in liquid form. A nipple 8, having a reduced admission opening 9 controlled by a valve 10, is secured in passage 7. This valve is connected to a lever 11 mounted upon a bracket 12 suitably secured to head 4. A float 13 is secured to lever 11 at the other end thereof and coacts with the lever and valve 10 to control admission of liquid refrigerant to body 1a of the container.

The head 4 is further provided with an outlet passage 14 and an outlet tube 15 is secured in the inner end of this passage and extends inwardly into the upper portion of body 1a, the inner end of this tube being curved upwardly. An inlet pipe 16 is connected to the inlet passage 7, an exhaust pipe 17 being connected to the outlet or exhaust passage 14. The pipe 17 is connected to the intake of a compressor and the pipe 16 is connected to the outlet or discharge of the compressor, the vaporized refrigerant being withdrawn from the upper portion of the container and compressed and returned to the lower portion of the container in liquid form.

Suitable valves are provided in the passages 7 and 14 for controlling the effective size thereof in a known manner. These valves and the functions thereof are well known in the art and need not be illustrated

nor described in detail. The container, as a whole, is, in general, of known construction. It is particularly pointed out, however, that the body 1a is continuous and unbroken throughout its whole extent.

The body or shell of the container is drawn in a single piece and is formed of copper, brass, or other suitable material possessing high heat conductivity. A tubular casing 18 is disposed at each side of body 1a and is suitably connected thereto in such manner as to have an efficient thermal connection therewith, this casing being spaced from the body 1a at 19.

The casing 18 is formed of copper or brass, or other suitable material which is a good conductor of heat, and is closed, at the end thereof adjacent head 4, by a cap 20. This cap is not essential, however, and may be omitted if desired. Fins 21 extend about body 1a of the container and are secured thereto and to the top and bottom and side walls of the casings 18 in a suitable manner, as by soldering, so as to have efficient thermal connection with the casings and the body of the container. These fins 21 are also formed of material which is highly efficient as a conductor of heat, such as copper, brass, or other suitable material.

The unit thus constructed is compact and of strong and durable construction, the casings 18 serving to connect and effectively brace the fins 21 so that the entire structure possesses desired rigidity.

This unit is intended to be mounted in a compartment 22 of a refrigerator construction 23. We have illustrated the unit as supported upon suitable brackets 24 secured to the side walls of the compartment, the fins 21 seating edgewise upon these brackets.

The brackets are of elongated U-shape in plan so as to provide suitable openings 25 to permit circulation of air upwardly therethrough as indicated in Fig. 5. The casings 18 are extended somewhat beyond end 2 of body 1a of the container through a finishing or facing plate 26, the outer ends of these casings being beaded over and suitably secured to this plate. Plate 26 serves to close an opening 27 in a closure plate 28 suitably secured in the front of the compartment 22. The opening 27 is of proper size to permit insertion of the unit into the compartment and positioning thereof upon the brackets 24.

It will be noted that the unit is disposed with the head 4 toward and adjacent the back of the compartment. When the unit is in place, the plate 26, in addition to serving as a closure for the opening 27, also serves to cover up the unit so that the structure as a whole presents a neat and finished appearance.

The casings 18 receive ice trays 29 of known construction which are inserted into and withdrawn from the casings from the outer ends thereof. Casings 18 are provided

with upwardly extending elements 30 pressed in the bottom wall thereof and serving to space the ice tray 29 away from the bottom wall of the casing so as to prevent freezing of the tray to the casing due to collection of moisture between the tray and casing.

When the ice tray is in position within the casing, it is surrounded thereby and is thermally connected, by means of the casing and the fins to the body 1a of the container. The warmer air within the compartment 22 flows upwardly along the sides of the compartment and through openings 25 of brackets 24 into contact with the casings 18 and fins 21. The casings and the fins, being good heat conductors, extract the heat from this relatively warm air and conduct it to the container, this heat being utilized to vaporize the refrigerant. The air is thus cooled and the relatively cold air flows downwardly about the unit and from the lower portion thereof into the compartment, as indicated in Fig. 5. A continuous circulation of air is thus maintained and the heat is quickly extracted from this air which passes over the fins and casings which provide an exposed surface of relatively great area which is thermally connected to the body of the container and, through this body, by heat conduction, to the body of refrigerant therein.

It is to be particularly noted that the container for the refrigerant is completely sealed against escape of the refrigerant otherwise than through the outlet passage 14. This container is provided with but two passages, the inlet passage 7 and the outlet passage and the body 1a is free of all joints or connections which might possibly be broken or opened due to handling or other causes resulting in leakage of the refrigerant. It is also noted that there is no possibility of leakage of the refrigerant due to a defective joint caused by improper soldering of a pipe or tube or other element into the body of the container. Also, by avoiding the necessity for hand soldering the tubes or pipes into the body of the container, we provide a unit which can be produced at much less cost than the present type of unit now in use.

While we have illustrated and described a preferred form of our invention, we do not limit ourselves to the particular construction shown since our invention, in its broader aspects, is directed broadly to the idea of a container free of joints or connections, and heat conducting members thermally connected to the container and extending therefrom into the compartment of the refrigerator structure.

A further advantage of our construction is the disposal of the head 4 at the inner end or rear of the unit. By having this head at the inner end of the unit, the tubes or pipes

16 and 17 leading to the condenser can be connected to the head 4 in the most convenient position and these tubes or pipes do not in any way interfere with inserting the ice trays into or withdrawing them from the casings 18. To facilitate connection of the pipes 16 and 17, the compartment 22 may be provided with a suitably disposed opening and closure means therefor, as is known in the art.

It will be noted that the fins 21 extend completely about and enclose the casings 18. This is advantageous as expediting freezing of the water in the trays 29.

What we claim is:

1. In a refrigerating unit, a container for a refrigerant, said container being a good conductor of heat, a plurality of heat conducting fins secured upon the container in thermal connection therewith, and casings of heat conducting material secured to the fins, said casings being adjacent to but separated from said container and having thermal connection therewith, said casings being adapted for reception of ice pans, and also serving as baffles which direct air streams around said container.

2. In a refrigerating unit, a container for a refrigerant, said container being a good conductor of heat, and a plurality of substantially rectangular heat conducting fins secured upon the container in thermal connection therewith, the fins being disposed transversely of the container, and means carried by said fins for directing descending air around said container.

3. In a refrigerating unit, a container for a refrigerant, said container being a good conductor of heat, casings spaced from the sides of but having thermal connection with the container, said casings being good conductors of heat and adapted for reception of ice trays, and fins secured to the container and the casings in thermal connection therewith, said fins and casings together serving to direct the air that is to be cooled by the unit around said container.

4. In a refrigerator having a chamber that is to be cooled, a refrigerating unit comprising a horizontal drum, substantially rectangular fins attached to said drum, means for supporting said fins in said chamber with their major axes horizontal to thereby support the drum in said chamber, said fins and supporting means being positioned so that the warmed air in said chamber will rise in the space beyond the ends of the fins, box like freezing chambers supported by said fins and located one on each side of said drum and adjacent to but not touching it, said chambers forming baffles which direct said air around said drum as it descends.

5. In a refrigerator, a chamber bounded in part by parallel vertical walls, brackets projecting from said walls near the top of

said chamber, a plurality of substantially rectangular fins supported by said brackets, a refrigerating drum supported by said fins and located substantially midway between said walls, cooling casings supported by said fins, said casings being spaced away from said walls and from said drum and serving as baffles for directing the circulation of air in said chamber.

10 6. In a refrigerator, a chamber bounded in part by parallel vertical walls, brackets projecting from said walls near the top of said chamber, a plurality of substantially rectangular fins supported by said brackets, said fins being vertical in said chamber and being substantially parallel to each other, a refrigerating drum supported by said fins and located substantially midway between said walls, cooling casings supported by said fins, said casings being spaced away from said walls and from said drum and serving as baffles for directing the circulation of air in said chamber.

25 7. In a refrigerator, a chamber bounded in part by parallel vertical walls, brackets projecting from said walls near the top of said chamber, a plurality of substantially rectangular sheet metal fins supported vertically between said brackets and disposed normal to said walls, a refrigerating drum supported by said fins and located substantially midway between said walls, cooling casings supported by said fins, said casings being spaced away from said walls and from said drum and 30 serving as baffles for directing the circulation of air in said chamber.

35 8. In a refrigerator, a chamber bounded in part by parallel vertical walls, brackets projecting from said walls near the top of said chamber, a plurality of substantially rectangular sheet metal fins supported vertically between said brackets and disposed normal to said walls, a refrigerating drum supported by said fins and located substantially 40 midway between said walls with its axis parallel to said walls, cooling casings supported by said fins, said casings being spaced away from said walls and from said drum and 45 serving as baffles for directing the circulation of air in said chamber.

In witness whereof, we hereunto subscribe our names this 25th day of February, 1930.

WILLIAM E. BIHL.
AXEL RAMCLAW.
